VALVE CLEARANCE GAUGE

Albert F. E. Schemmel, Alvord, Iowa

Application February 13, 1950, Serial No. 143,841

4 Claims. (Cl. 33—181)

1

This invention comprises novel and useful improvements in a valve clearance gauge and more specifically pertains to an improved means for facilitating the reconditioning of automobile poppet valves and for adjusting the length and clearance of the same after a valve re-grinding operation.

The principal object of this invention is to provide an apparatus which will simplify and render more efficient and economical the operation of reconditioning and adjusting poppet valves of internal combustion engines and similar devices.

A further important object of the invention is to provide an improved valve clearance gauge for determining the requisite length to which a valve and its valve stem should be adjusted for efficient operation in the machine after the valve has been ground upon its seat.

A further important object of the invention is to provide a valve clearance gauge in conformity with the foregoing object which may be easily, accurately and more satisfactorily adjusted for determining the desired clearances of various sizes and types of valves in their valve assemblies.

Still another important object of the invention is to provide a valve clearance gauge as set forth in the foregoing objects wherein the device may be readily adjusted to indicate and gauge various types, dimensions, and sizes of valves and for effecting any desired clearance between the valve and its actuator after a valve-grinding operation has been performed.

A still further important object of the invention is to provide an improved valve grinding jig for holding the valve stem against an abrasive wheel for removing excess material therefrom and for effecting a grinding of the valve stem to any desired length.

These, together with various ancillary features and objects of the invention which will later become apparent as the following description proceeds, are attained by the present invention, a preferred embodiment of which has been illustrated, by way of example only, in the accompanying drawings, wherein:

Figure 1 is a fragmentary vertical sectional view through a portion of the valve assembly of an internal combustion engine or other mechanism and showing the improved valve clearance gauge positioned therein;

Figure 2 is a fragmentary side elevational view of a portion of a valve adjusting grinder with the valve clearance forming the subject of this

2

invention applied thereto and illustrating its operation in setting the device;

Figure 3 is a fragmentary view, similar to Figure 2 but showing the placing of a valve in the jig after the latter has been set in accordance with the valve clearance gauge;

Figure 4 is a top plan view of the valve clearance gauge illustrating the indicating means therefor;

10 Figure 5 is a vertical longitudinal sectional view through the valve clearance gauge disclosed in Figure 1; and

Figure 6 is a side elevational view of a portion of the valve clearance gauge.

15 Referring now more specifically to the accompanying drawings, wherein like numerals designate similar parts throughout the various views, attention is directed first to Figure 1 wherein there is disclosed at 10 a portion of the cylinder 20 of an internal combustion engine or other apparatus which is provided with control valves, a portion of the assembly of the valve mechanism being illustrated as including a conical or tapered valve seat 12 together with a cylindrical passage or port 14 in which is removably installed the conventional valve stem guide, the conventional valve assembly further including a valve actuator, such as a tappet, or the like, 16 adapted to be reciprocated by a valve actuating cam 18 in accordance with conventional and well-known practice in the internal combustion engine art or other analogous fields.

20 When it becomes necessary to clean and recondition the seating engagement of the conventional poppet valve, the same including a valve stem 20, a valve head 22 having a conical valve seating surface 24 thereon, as shown in Figure 3, the customary guide bushing, not shown, is removed from the valve guide bushing passage 14, and the valve head 22 is rotated in any suitable manner to cause a grinding of the complementary surfaces of the valve head 24 and the valve seat 12 to reestablish a serviceable seating engagement between these elements.

25 However, since this valve grinding operation necessarily abrades or removes considerable material from the coacting surfaces of the valve seat and the valve head, the bottom end of the valve stem which abuts the valve tappet or actuator 16 is correspondingly lowered, thereby diminishing the customary necessary operating clearance between the actuator and the bottom of the valve stem. After the valve grinding operation has been completed, it therefore becomes 30 necessary to remove certain excess material from

the bottom of the valve stem in order to restore this desired clearance between the actuator and the stem to the requisite tolerance or dimension.

Since, however, the amount of material which it is required to remove from the bottom of the valve stem after a valve grinding operation varies with each valve, it is necessary to accurately measure or gauge the overall distance from the seating surface 24 on the valve head 22 and the upper surface of the valve actuator 16.

It is the primary function and purpose of this invention to provide an improved means for accurately gauging this distance, and thereafter determining the amount of material which must be removed from the bottom of the valve stem in order to restore the desired clearance between the same and the top of the valve actuator.

The improved valve clearance gauge intended to perform this purpose, as illustrated in Figure 5, consists of a shaft or rod 26 of any suitable length constituting a stem, the opposite extremities of this stem being screw-threaded, as at 28 and 30. At its lower end, the stem has screw-threadedly engaged upon the threads 30 the internally threaded bore of a boot 32 provided with a foot portion 34 adapted to engage and seat upon the top of the valve actuator 16. It is contemplated that a series of interchangeable boots 32 could be provided, of varying lengths, whereby the gauge would be readily adapted to the measuring of various sizes and types of valves. Slidably received upon the shaft 26 is a sleeve 36, see Figure 6, which has integrally formed upon its upper end, or rigidly attached thereto in any desired manner, a dummy valve body 38. This dummy valve body is provided with a conical surface 40 which is of substantially the same contour and shape as the seating surface 24 on the poppet valve head 22, to thereby engage the seat 12.

Obviously, the extend of the surface 40 will be such as to engage the seats 12 of different sizes of valves in order to adapt the device to function with a plurality of types and makes of valve mechanisms.

As above mentioned, the sleeve 36 is slidably received upon the stem 26, but is keyed to the same to prevent relative rotation therebetween. For this purpose, the sleeve, as shown in Figure 6, is provided at its lower portion with a longitudinally extending slot or guideway 42 for slidably but non-rotatably engaging a key 44 in the form of a pin or the like, and which is carried by and extends laterally from the side of the stem 26 at an appropriate position thereon. As will now be apparent from Figure 5, the sleeve 36 and the dummy valve head 38 are free to move slidably longitudinally of the stem 26, but are restrained and prevented against relative rotation with respect thereto.

Adjacent its lower end, a bushing 46 is slidably received upon the sleeve 36, and retained thereon as by a set screw or the like 48 in various longitudinally adjusted positions. This bushing serves the dual functions of enclosing the guide slot 42 and the key 44, and preventing lateral displacement of the key from the guide, and further functions as a guide bushing, as shown in Figure 1, for guiding the gauge in the valve bushing passage 14. A resilient means in the form of a coiled compression spring 50 is provided which encircles the lower portion of the stem 26, and is seated against the upper surface of the boot 32, and is received within the lower portion of the guide bushing 46, and abuts the lower end of the sleeve 36. This resilient means yieldingly urges

the sleeve 36, and consequently the dummy valve 38 upon the valve stem outwardly from the boot 32, to thereby yieldingly tend to increase the overall length of the valve clearance gauge.

In order to accurately adjust the length of the valve gauge against the bias of the spring 50, an adjusting nut 52 is provided which is internally threaded to engage the threaded extremity 28 of the valve stem, this nut being preferably provided with a knurled finger grip portion 54 as shown in Figure 1. At any convenient place thereon, this adjusting nut is provided with a trammel or indicating pointer 56 which is positioned to overlie the flat annular top surface of the dummy valve head 38, and to cooperate with suitable indicating indicia 58 thereon, as shown in Figure 4.

Preferably, the pitch of the threaded portion 28 is such that one complete rotation of the adjusting nut 52 will permit, in part or effect, a predetermined axial or longitudinal movement of the dummy valve head 38 with respect to the bottom portion 34 of the boot 32. Thus, if twenty-eight threads per inch are provided, one complete turn of the adjusting nut will result in a movement of thirty-five one-thousandths of an inch of the dummy valve head toward or from the bottom surface of the boot 32, thus varying the distance from the engagement of the seating surface 40 of the dummy head 38 and the valve seat 12 from the top of the valve actuator 16 by 35-thousandths of an inch. The indicia 58 will thus indicate by thousandths of an inch, or fractional portions of a rotation of the adjusting nut 52, any desired variation from this length.

In the use of this gauge, the latter is inserted in the valve seat 12 and through the valve passage 14 as shown in Figure 1, with the bottom portion 34 of the boot 32 resting upon the top surface of the valve actuator 16 when the valve actuating cam 18 is in its idle position as shown in Figure 1.

It is now merely necessary to rotate or adjust the adjusting nut 52 until such time as the surface 40 just seats upon the valve seat 12, while the bottom surface 34 of the boot 32 engages the top surface of the actuator 16, at which time the effective length of the gauge will be equal to the distance between the valve seat and the actuator. In order to set the gauge for imparting the desired clearance to the valve stem, it is merely necessary to rotate the adjusting nut 52 through their proper angular interval as indicated by the indicia 58, to shorten the length of the gauge by the amount of clearance desired. With the gauge so adjusted, the latter is now ready to properly adjust the valve stem grinder for, at one operation, providing the proper length to the valve stem which has been reconditioned in its valve seat.

Referring now to Figures 2 and 3, it will be seen that the valve grinder comprises a conventional abrasive wheel 60, mounted for rotation upon an arbor or shaft 62 by any desired means, the face or side 64 of this wheel serving as the abrasive surface for removing excessive material from the bottom end of the valve stem 20 which is to be pressed thereagainst. The valve stem grinder further includes a supporting jig which may conveniently comprise a substantially U-shaped bracket indicated at 66, which is fixedly but adjustably secured by any suitable supporting means, such as that indicated diagrammatically at 68, with respect to the abrasive wheel. This supporting jig may conveniently comprise parallel vertical supporting standards 70 and 72

which may be provided with V-notches in their upper surface for slidably and rotatably receiving and supporting a valve stem 20 therein, as shown in Figure 3. An adjustable stop means in the form of a bar or slide 74 is slidable through aligned apertures in the supports 70 and 72, in parallel relation to the member supported by these standards. The bar 74 is yieldingly urged away from the abrasive wheel 60, as by a coiled compression spring 76 which embraces the bar and terminally abuts the standard 72, and an adjustable collar 78 adjustably secured upon the bar 74. Although yieldingly urged away from the abrasive wheel, the bar 74 may be locked in various adjusted positions, as by a set screw or the like, as indicated at 80, and which is screw-threaded through the standard 70 and adapted to engage the side of the bar 74.

At its outer end, beyond the standard 70, the bar 74 is provided with a set of stop jaws 82 and 84 of any desired character, which are provided with conical stop surfaces 86, corresponding to the conicity of the seating portion 24 of a valve stem and to the seating portion 40 of the dummy valve head 38.

The operation of this jig is as follows: The locking or fastening screw 80 is released, whereupon the spring 76 will urge the stop member 74 toward the left, as viewed in Figures 1, 2 and 3. The clearance gauge, adjusted in the manner previously described for obtaining a desired length of valve stem, together with the desired clearance, is now placed in the V-shaped notches of the supporting standards 70 and 72 of the jig 66, with the foot portion 34 of the boot 32 disposed against the surface 64 of the abrasive wheel 60, whereby the engagement of the surface 40 with the top surfaces 86 of the jaws 82 and 84 will cause a sliding movement of the bar 74 against the resistance of the spring 76, until the bottom or foot portion 34 has been properly seated against the surface 64. In this position, the screw 80 is then tightened and the gauge member removed, it being noted that the surfaces 86 will now be positioned at the same distance from the surface 64 of the abrasive wheel as it is desired to obtain for the compensated distance by the valve seat 12 to the top of the valve actuator 16.

The valve stem is then inserted in the V-shaped notches, as shown in Figure 3, and it will be noted that because of the excessive length of the valve stem that the foot of the same will engage against the surface of the abrasive wheel, while the valve head will be spaced from the stop surfaces 86 as by a clearance indicated generally at 88 in Figure 3. The valve stem will now be held in place and pressed toward the abrasive wheel, as the latter is rotated, until the necessary amount of material has been removed from the foot of the valve stem, it being noted that as this material is removed, the valve stem will be shifted or pushed toward the right, until the valve seat-

ing portion 24 abuts or engages and rests upon the stop surfaces 86. At this time, further movement toward the right of the valve stem is prevented, and the amount of material removed from the valve is thus limited to obtain the desired clearance between the valve stem and the valve actuator.

From the foregoing, the operation of the device together with its many advantages will be readily understood, and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claims.

Having thus disclosed and described the invention, what is claimed as new is as follows:

1. A valve clearance gauge comprising a stem, a sleeve having a dummy valve thereon slidable upon said stem, means preventing rotation of said sleeve during sliding movement, a guide bushing adjustably secured to said sleeve and enclosing said rotation preventing means, a boot removably secured to one end of said stem for engaging a valve actuator, resilient means abutting said boot and sleeve and urging the sleeve from the boot, adjusting means engaging the other end of the stem and retaining the sleeve thereon for varying the distance between the dummy valve and the end of the boot.
2. The combination of claim 1 wherein said bushing surrounds one end of said resilient means.
3. The combination of claim 1 wherein said adjusting means comprises a nut threaded upon the stem, said nut and dummy valve having cooperating indicia.
4. The combination of claim 1 wherein said rotation preventing means comprises a key extending laterally from said stem, said sleeve having a key slot slidably receiving said key.

ALBERT F. E. SCHEMML.
